UNITED STATES PATENT OFFICE.

HARRY M. CLOUDE, OF CINCINNATI, OHIO.

PUMPING DEVICE FOR AUTOMOBILES.

1,237,869.

Specification of Letters Patent. Patented Aug. 21, 1917.

Application filed May 19, 1916. Serial No. 98,688.

To all whom it may concern:

Be it known that I, HARRY M. CLOUDE, a citizen of the United States, and a resident of Cincinnati, in the county of Hamilton and State of Ohio, have made certain new and useful Improvements in Pumping Devices for Automobiles, of which the following is a specification.

My invention relates to pumping devices for automobiles, and it consists in the combinations, constructions and arrangements herein described and claimed.

An object of my invention is to provide a device which may be readily applied to automobiles of the existing types, and by means of which air may be supplied to the tires.

A further object of my invention is to provide a device of the type described which 20 may be readily removed.

A further object of my invention is to provide a pumping device in which the power is derived from the rear wheels of the automobile, and in which means is provided for 25 the successful operation of the device, even though the pump may be slightly out of alinement with the crank pin carried by the wheel.

A further object of my invention is to provide 30 a novel form of pitman which is extensible and which is provided with joints which insure the successful operation of the device when the parts are not in alinement, as stated.

Other objects and advantages will appear 35 in the following specification, and the novel features of the device will be particularly pointed out in the appended claims.

My invention is illustrated in the accompanying drawings forming part of this application, in which:—

Figure 1 is a side view of the device.

Fig. 2 is a section on the line 2—2 of Fig. 1.

Fig. 3 is a section on the line 3—3 of Fig. 2.

Fig. 4 is a section along the line 4—4 of Fig. 2.

Fig. 5 is a section on the line 5—5 of Fig. 1.

Fig. 6 is a detailed view of a portion of the device shown in Fig. 1.

Fig. 7 is a perspective view of one of the pump brackets.

Fig. 8 is a perspective view of the other of the pump brackets.

Fig. 9 is a perspective view showing the means for connecting the pitman to the wheel, and

Figs. 10 and 11 are views showing modified forms of connecting pins.

In carrying out my invention I make use of the rear wheel of the automobile as the driving means for the pump. In Fig. 1 I have shown an automobile which I have denoted in general by A. This is provided with a rear wheel W having the usual hub plate 1. Secured to the hub plate 1, is a bracket 2 of the shape shown in Fig. 9, this bracket having preferably a moon-shaped base 2^a to which the body portion of the bracket 2 is integrally secured, and being provided with a connecting pin 2^b having a recess 2^c therein. At the end of the body portion 2 is a slot 2^d. 75]

Arranged to coöperate with the connecting pin 2^b is a crank pin 3, which is provided with a base portion 3^a having an opening 3^b therethrough, arranged to fit over the pin 2^b, and having a set screw 3^c arranged to enter the recess 2^c in the pin 2^b, so as to firmly secure the crank pin to the bracket. In order to further prevent the rotation of the crank pin with respect to the connecting pin 2^b, I provide lugs 3^d on each side of the portion 3^a which are arranged to enter the slot 2^d. A further purpose of these lugs is to center the crank pin, that is to say, to insure its extending at right angles to the face of the plate 1. 90

It will be understood that each rear wheel may be provided with a pumping device like that about to be described, and to this end the pins 3 are provided with bases having lugs 3^d on each side, so as to make either a left or a right connection, depending upon the side to which the pin is applied. 95

In Fig. 9 I have shown one end of the pitman in detail. This consists of a bearing portion 4^a arranged to surround the cylindrical portion of the crank pin 3, and having an integral laterally extending plate or arm 4^b provided with an opening 4^c. The plate 4^b is arranged to enter a slot 4^d in a telescopic portion 4^e, the latter being provided with an opening 4^f arranged to register with the opening 4^c. A pin 5 forms a pivotal connection between the parts 4^b and 4^e. 105

It will be observed that the part 4^b is of considerable length, and the purpose of this is to form a long bearing so that there will not be any play in the rod in a plane at right 110

angles to the slot 4^a, but there may be play or relative movement between the parts 4^b and 4^c with the pin 5 as a pivot.

Arranged to fit on the outside of the part 5 4^c is a telescopic portion 4^e, which is connected to the member 4^b by a pin 5', the member 4^b being integrally connected with a portion 6^a similar to the portion 3^a of the crank pin. The latter is provided with a bore or 10 recess 6^b (see Fig. 2) shown in dotted lines, arranged to receive a pin 7 carried by a plate 8, which has an arm 9 pivotally connected at 10 to a slotted arm 11 carried by a yoke or cross-head 12, to which piston rods 15 and 14 are connected. The former, as 15 will be seen from Fig. 1, extends into a large pump cylinder 15, and the latter into the small pump cylinder 16. A set screw 17 permits the extension of the telescopic parts 4^c and 4^e of the pitman.

The means for securing the pump to the running board of the automobile is as follows:

Secured to the running board 18 (see 25 Figs. 6 and 7) is an L-shaped bracket 19 having extending therefrom a pin 20 arranged to enter an opening 21^x in the foot plate 21 of an ordinary double acting pump having the cylinders 15 and 16. A locking pin or cotter pin 22 is secured by a chain 23 to a portion of the bracket and may be inserted through an opening in the pin 20, so as to firmly lock the pump to the bracket.

At the opposite end of the pump is a 35 bracket like that shown in Fig. 8 having a base portion 24^a arranged to be secured to the underside of the running board 18 and provided with curved recesses 24^b and 24^c respectively arranged to receive the cylinders 15 and 16, a spacing member 24^d being provided which extends between the cylinders and through which a locking pin 25 which is attached to a chain 26 may extend.

45 From the foregoing description of the various parts of the device the operation thereof may be readily understood.

The plate 1 with the bracket 2 is always in position on the wheel and the pump may be carried underneath the running board or it may be carried elsewhere on the automobile. If now a tire needs inflating the pump is secured to the bracket 18 by passing the pin 20 through the opening 21^x in the base 21 of the pump and inserting the locking pin 22, the opposite end of the pump being placed in position, as described, and the chain 26 being brought around underneath the pump, when the pin 25 may be inserted in the opening in the spacing member 24^d, thus locking the pump securely in position. The crank pin 3 may now be connected to the connecting pin 2^b and the

pin 7 may be inserted in the opening 6^b where it may be securely held by the set screw 6^d, see Figs. 1 and 2. During the placing of the pitman in place, the set screw 17 is loosened so that part may be adjusted to the right length, and then the set screw is tightened. The automobile is jacked up 70 so as to lift the rear wheel W from the ground and the engine is started.

Owing to the construction of the pitman the pivotal connection of the cross-head 12 need not be exactly in alinement with the pivotal connection of the pitman with the crank pin. Nevertheless, the pitman will transmit rotary movement of the wheel to the pump without binding and without lost motion.

When the wheel is pumped up, the two set screws 3^c and 6^d may be unloosened, and the pitman instantly removed. The removal of the pump of course is the work of a moment in withdrawing the locking pins 85 which hold the pump to the brackets.

As stated, the device may be used on either side of the machine, the one pitman serving for both wheels.

In Figs. 10 and 11 I have shown a modified form of connecting pin. In Fig. 10 the pin 2^{bx} is square in section, while in Fig. 11 the pin 2^{by} is hexagonal in section.

I claim:

1. In a pumping attachment for automobiles, a bracket secured to the hub plate of one of the wheels of the automobile, having a radial connecting pin, a crank pin having a socket arranged to receive said connecting pin, means for rigidly holding the crank pin 95 at right angles to the connecting pin, a pitman having a body portion made up of telescopic parts, end portions pivoted to said body portion so as to permit relative movement with respect to said body portion in a plane through the longitudinal axis of said pitman and at right angles to the plane of the driving wheel, one of said end portions being pivotally connected to said crank pin. 100

2. In a pumping attachment for automobiles, a bracket carried by the hub plate of the driving wheel of the automobile, said bracket being provided with a connecting pin and a slot, a crank pin having a bore 115 arranged to receive said connecting pin and having a lug arranged to enter the slot in said bracket for holding the crank pin in position, a set screw for securing the crank pin to said connecting pin, a pitman having a telescopic body portion, means for adjustably securing the telescopic portions in their shifted position, said pitman also having a pivotal end portion pivotally connected with said crank pin. 120

HARRY M. CLOUDE.
